F. H. N. GERWIG,
CINDER RUNNER FOR BLAST FURNACES.
APPLICATION FILED JULY 10, 1918.

1,286,991.

Patented Dec. 10, 1918.

UNITED STATES PATENT OFFICE.

FREDERICK H. N. GERWIG, OF BRADDOCK, PENNSYLVANIA.

CINDER-RUNNER FOR BLAST-FURNACES.

1,286,991.

Specification of Letters Patent. Patented Dec. 10, 1918.

Application filed July 10, 1918, Serial No. 244,227.

To all whom it may concern:

Be it known that I, FREDERICK H. N. GERWIG, a citizen of the United States, and resident of Braddock, in the county of Allegheny and State of Pennsylvania, have invented certain new and useful Improvements in Cinder-Runners for Blast-Furnaces, of which the following is a specification.

My invention relates to the construction of 10 the runners or troughs used in conducting molten cinder or slag from the cinder notch of blast furnaces and from the cinder overflow outlet of the iron runner of blast furnaces to the cinder ladle cars used in transporting the cinder in a molten condition.

In operating blast furnaces it is desirable and generally necessary to clean out the cinder runners after each flushing operation by removing the film or layer of cinder 20 which chills and solidifies on the sides or walls of the cinder runner during each under tapping or flushing operation. It also is a frequent occurrence for a sudden rush of cinder from the furnace to overflow the 25 cinder runner and result in large quantities of molten cinder being spilled over the walls of the cast-house onto the depressed cinder tracks on which the cinder ladle cars are standing. The result is to cause delays in 30 the removal of the cinder cars and added expense for the labor used in removing the spilled cinder from the tracks, movement of the cinder cars sometimes being prevented until after the spilled cinder is removed 35 from the car tracks.

In removing the layer of chilled cinder from the cinder runners or troughs, large amounts of broken cinder fall to the depressed car tracks, which is also a cause of 40 delay and considerable expense in removing the spilled cinder from the tracks.

One object of my invention is to provide 45 a cinder runner for blast furnaces having novel means whereby the spilling of cinder on the cinder car tracks, heretofore caused in cleaning out accumulations of chilled cinder in the cinder runner or by rushes of molten cinder overflowing the cinder runner and falling over the walls of the cast house, is 50 overcome and prevented and whereby the delays and expense occasioned by the removal of spilled cinder from the car tracks are avoided and made unnecessary.

The invention consists in the provision of 55 upwardly projecting extension walls or side-

boards on the cinder runners or troughs, adjacent to the overhanging spouts or discharge ends of the spouts and application of toe angles extending between the side-boards of contiguous spouts, so as to cause 60 overflows of molten cinder or pieces of the chilled cinder handled in cleaning the cinder runners to be discharged into the ladle cars, and to prevent the cinder from flowing or falling to the car tracks below the cinder 65 runner spouts.

Referring now to the drawings, forming part of this specification, Figure 1 is a diagrammatic plan showing the cinder runners or troughs of a blast furnace constructed 70 and arranged and adapted for use in accordance with my invention.

Fig. 2 is a sectional elevation showing part of the apparatus of Fig. 1, the section being taken on the line II—II of Fig. 1. 75

Fig. 3 is a sectional elevation similar to that of Fig. 2, showing the application of the toe angles forming part of my invention, the section being taken on the line III—III of Fig. 1. 80

Fig. 4 is a sectional elevation on the line IV—IV of Fig. 1.

Fig. 5 is a sectional end elevation, similar to Fig. 4, showing a modification in the construction and arrangement of the side boards 85 or extensions forming part of my improved apparatus.

In the accompanying drawings, the numeral 2 designates a blast furnace having cast-house walls 3 at the sides of the cinder 90 car tracks, and 4 is the ladle of molten cinder cars which are positioned or "spotted" on depressed railway tracks so as to be located under the overhanging discharge ends or spouts of the branches on the cinder 95 runner or trough.

The cinder trough or runner 5, which slopes downwardly away from the cinder notch, extends from the blast furnace cinder notch to the runner 6, and the cinder runner 6 extends to one of the cinder ladle cars 4 from the iron runner or trough 7, which is used in conducting molten iron from the iron notch or tapping hole of the blast furnace to the iron ladle cars (not shown). The cinder runner 6 is provided with discharge spouts 8, 9, 10, 11, and 12, as is clearly shown in Fig. 1.

The overhanging ends of the spouts 9, 10, 11, and 12 are provided with side walls or 110

2
side-boards 13 which project upwardly and form a novel feature of this invention. Preferably the side-boards 13 will be rigidly secured in place by means of bolts fastened in the walls 3 of the cast-house. When found necessary or desirable, the extensions or side-boards 13 will flare upwardly and outwardly, as shown in Fig. 5. The extensions or side-boards 13 also may be separate from instead of being formed integrally on the spouts of the cinder runner. In other cases the side boards may be formed integrally and provided with the bolt holes for the fastening bolts used in securing the cinder runner spouts in place in position to discharge into the ladles 4 of the cinder cars.

Extending between the adjoining side-boards 13 of the spouts 9, 10, 11 and 12 are toe angles 14 which have one leg 15 projecting upwardly above the level of the wall 3 (see Fig. 3) so as to form a side-board connecting the side-board 13 of adjacent spouts. The toe angles 14 will be bolted or otherwise fastened on the top of the wall 3, as will be readily understood.

In handling cinder with troughs or runners embodying my invention, the molten cinder is conveyed by the runners to the ladles 4 of the cinder cars in the usual manner. Should a sudden rush of cinder occur, (such as would overflow the runner and fall onto the depressed tracks with cinder runners of the usual construction,) the excess flow of molten cinder to the tracks is prevented from falling to the car tracks by the side-boards 13 and toe angles 14, and is retarded and caused to flow over the end of the spouts into the ladles 4.

When cleaning the cinder runners after each flushing operation, the layer of solidified cinder in the runners is broken up into pieces and the broken pieces of solidified cinder are swept or shoveled toward the spouts or discharge end of the branch runners. When a point adjacent to the spouts is reached in the cleaning operation, the workmen continue the sweeping or shoveling, as heretofore, but instead of considerable quantities of the broken cinder falling over the walls 3 of the cast-house to the car tracks, the side-boards 13 and toe angles 14 will catch and retard such pieces of cinder and will deflect and cause them to be discharged into the ladle 4 located below each of the several discharge spouts of the cinder runner.

The advantages of my invention, which will be apparent to those skilled in the art, arise from the prevention of any cinder being spilled onto the cinder-ladle car tracks during the flushing and runner cleaning operations, and from the avoidance of delays and saving in labor caused heretofore in

removing accumulations of spilled cinder from the cinder car tracks.

Various modifications in the construction and arrangement of cinder runners embodying my invention may be made without departing from the invention as defined in the appended claims.

I claim:

1. A blast furnace cinder runner comprising, in combination, a main runner, a spout on the runner, and upwardly and outwardly inclined extensions on the opposite side walls of said spout, said extensions projecting above the plane of the upper edges of the sides of the main runner.

2. A blast furnace cinder runner comprising, in combination, a main runner, a spout on the runner, upwardly and outwardly inclined extensions on the opposite side walls of said spout, said extensions projecting above the plane of the upper edges of the sides of the main runner, and toe angles on opposite sides of said spout.

3. A blast furnace cinder runner comprising, in combination, a main runner, said runner having a spout and, integrally formed extensions on the opposite side walls of said spout, said extensions projecting upwardly and outwardly above the plane of the upper edges of the sides of the main runner.

4. A blast furnace cinder runner comprising, in combination, a main runner, said runner having a spout and integrally formed extensions on the opposite side walls of said spout, said extensions projecting upwardly and outwardly above the plane of the upper edges of the sides of the main runner, and toe angles on opposite sides of said spout.

5. A blast furnace cinder runner comprising, in combination, a main runner having a plurality of branch troughs thereon, a spout on the end of each branch trough, upwardly and outwardly inclined extensions on top of the opposite side walls of said spouts, said extensions projecting materially above the plane of the upper edges of the sides of the branch troughs, and toe angles extending between and connecting the adjacent extensions of contiguous spouts.

6. A blast furnace cinder runner comprising, in combination, a main runner having a plurality of branch troughs thereon, an overhanging spout on the end of each branch trough, upwardly and outwardly inclined extensions on top of the opposite side walls of said spouts, said extensions projecting materially above the plane of the upper edges of the sides of said branch troughs, and toe angles extending between and connecting the adjacent extensions of contiguous spouts.

In testimony whereof, I have hereunto signed my name.

FREDERICK H. N. GERWIG.
